Fig. 2.

Diagram illustrating a circular pattern with a central hexagonal hole. The pattern is divided into 12 equal sectors by radii. The sectors are labeled with the following numbers: 27, 26, 24, 20, 27, 26, 21, and 25. Three ovals, each labeled '30', are positioned in the sectors. The first oval is in the top-left sector, the second is in the bottom-right sector, and the third is in the middle-right sector.

UNITED STATES PATENT OFFICE.

JAMES ALFRED, OF BROCKTON, MASSACHUSETTS.

SHOE.

Application filed April 14, 1927. Serial No. 183,849.

The object of this invention is to provide means within the heel portion of a shoe to adjustably support the wearer's heel at different heights and inclinations, relative to the outsole and heel, so that the location of maximum pressure of the wearer's foot on the shoe bottom may be varied, and other useful ends attained.

Of the accompanying drawings forming a part of this specification,—

Figure 1 shows partly in side elevation, and partly in section, a portion of a shoe embodying the invention.

Figure 2 is a top plan view, showing the portion of the insole shown by Figure 1, and adjustable supporting means associated therewith, the shank stiffener being shown by dotted lines,

Figure 3 is a view similar to a portion of Figure 1, showing a different adjustment.

Figure 4 is a section on line 4—4 of Figure 3.

Figure 5 shows in perspective the heel plate shown by the preceding figures.

Figure 6 shows in perspective, and separated from each other, the members of one of the adjustable supports, and a portion of the shank stiffener extension hereinafter described, a portion of the heel plate being shown.

The same reference characters indicate the same parts in all of the figures.

The insole has a fore portion 12, a shank portion 13, and a heel portion 14. The insole is preferably split horizontally from its heel portion through the shank portion, to form a flap 15, whose chief function is to cover the adjustable heel plate hereinafter described, and bridge the space between said heel plate and the shank portion of the insole. The fore portion 12 and the shank portion 13 may be permanently attached in a welt shoe by inseam stitches, connecting a lip thereon with the welt 16 and upper 17 of a welt shoe, or it may be otherwise attached. The heel portion 14 is offset downward from the shank portion 13, as shown by Figures 1 and 3, during the lasting operation, to form a recess under the heel plate herein-described, a last being employed having a protuberance on the heel end of its bottom.

The outsole here shown includes a fore portion 18, a shank portion 19, and a heel portion 20. The usual or any suitable heel 21 may be attached to the heel portion of the

outsole by nails or other fasteners (not shown) which may engage the margin of the heel portion 14 of the insole.

To the under side of the shank portion 13 of the insole is attached, as by a rivet 22, a resilient shank stiffener 23, having an extension 24, projecting under the heel portion 14 of the insole, and preferably formed as indicated by dotted lines in Figure 2.

25 designates a heel plate which supports the wearer's heel and is located above the heel portion 14. The heel plate is formed to enter the above-described recess and is preferably dished, to conform to the bottom of the wearer's heel, and is supported by a plurality of adjustable supports, each composed of a nut 26, fixed to the shank extension 24, and a standard 27, which is a screw-threaded bolt extending through an orifice in the heel portion 14 of the insole, and engaged with the nut 26. Each standard 27 has a shoulder 28 (Figure 6) at the upper end of its threaded portion, and a reduced head 29, projecting above the shoulder and into a closely fitting orifice 30 (Figure 5) in the heel plate 25, the head being provided with a screw-driver-engaging slot 31.

The nuts 26 are preferably inserted in sockets formed in the heel portion 20 of the insole, and, if desired, in a lift of the heel 21. The heel plate 25 bears on the shoulders 28, so that when the standards 27 are raised or lowered by their rotation in the nuts 26, the heel plate is correspondingly raised or lowered. The length of the nuts 26 and standards 27 is such that the heel plate may be considerably raised as shown by Figure 1, and considerably lowered as shown by Figure 3, provision being thus made for shifting the wearer's weight forwardly on the shoe bottom by raising the heel plate.

I prefer to employ three of the adjustable supports, one being at the rear portion of the heel plate, and on the longitudinal median line thereof, while the other two are at the forward portion of the plate and at opposite sides of the median line, a three-point support being provided. By raising the standard 27 of the rear support, without raising the corresponding standards of the forward supports, a longitudinal inclination may be imparted to the heel plate, as indicated by dotted lines in Figure 3. By raising the standard 27 of one of the forward supports without adjusting the other standards, a transverse inclination may be impart-

ed to the heel plate, as indicated by dotted lines in Figure 4. By adjusting each of the standards 27, the heel plate may be maintained horizontally, either above the shank portion of the insole, and spaced from the bottom of the recess, as shown by Figure 1, or depressed into the recess, as shown by full lines in Figure 3.

The flap 15 is provided with orifices 32 (Figures 1, 3 and 4) which coincide with the heads 29 of the standards 27, when the flap is in position to cover the heel plate. The thickness of the flap is preferably somewhat greater than the projection of the heads 29 above the shoulders 28, so that the flap prevents the heads from touching the bottom of the wearer's heel or stocking. The flap bridges the space between the forward end of the heel plate and the upper surface of the shank portion 13 of the insole.

It will be seen that the insole, the shank stiffener 23, attached to the shank portion of the insole and having the extension 24, and the internally threaded nuts 26, fixed to the extension, constitute a unit which may be engaged with the insole and incorporated therewith in the shoe before the threaded standards 27, and the heel plate 25 are applied.

The heads 29 of the standards are preferably enlarged or upset at their upper ends, as shown at 29^a (Figures 4 and 6), to inseparably engage them with the heel plate 25, so that the plate cannot be separated from the standards, and the standards are freely rotatable in the orifices 30 of the heel plate. After the shoe is otherwise completed, the standards 27, thus engaged with the heel plate, are engaged with the nuts 26.

I claim:

1. A shoe comprising, in combination, a bottom including an outsole and a full length insole fixed to the outsole, the heel portion of the insole being depressed below the shank portion thereof, to form a recess below the foot-containing space in the shoe, a shank stiffener fixed in the bottom below the insole, the stiffener being curved to conform to the shank portion of the insole and having an extension conforming to the heel portion thereof, a plurality of nuts fixed to

the shank extension and embedded in the heel portion of the bottom, a heel plate formed to enter said recess, a plurality of screw-threaded standards inseparably engaged at their outer ends with the heel plate, to rotate therein, and extending through the heel portion of the insole into the nuts, the outer ends of the standards being formed to engage a screw-driver, and a flap connected with the shank portion of the insole, and formed to cover the heel plate, said flap being provided with screw-driver-receiving openings coinciding with the outer ends of the standards, the arrangement being such that the standards support the heel plate and flap at a plurality of points, and are vertically adjustable, so that the heel plate and flap may be maintained horizontally, either elevated above the shank portion of the insole, and spaced above the bottom of the recess, or depressed into the recess, the flap bridging the space between the forward end of the heel plate and the shank portion of the insole.

2. In a shoe, a full length insole, a shank stiffener attached to the shank portion of the insole, and having an extension projecting under the heel portion thereof, a heel plate located above the heel portion of the insole, and a plurality of adjustable supports for the heel plate, each including an internally threaded nut fixed to the shank extension and adapted to bear on the heel portion of the shoe, and an externally threaded standard adjustably engaged with the nut, said standards extending through the heel portion of the insole, and supporting the heel plate, the height of the heel plate being variable by rotation of the standards, there being three of said supports, one supporting the rear portion of the heel plate, and located at the longitudinal median line thereof, while the others support the forward portion of the plate and are located at opposite sides of said median line, the arrangement being such that said supports may be adjusted to impart either a longitudinal or a transverse inclination to the heel plate.

In testimony whereof I have affixed my signature.

JAMES ALFRED.
